CLAIM

The ornamental design for a three ring climbing playground apparatus, as shown and described.

DESCRIPTION

FIG. 1 is an orthographic view of a three ring climbing playground apparatus showing my new design;

FIG. 2 is a front view of the new design;

FIG. 3 is a right side view of the new design;

FIG. 4 is a rear view of the new design;

FIG. 5 is a left side view of the new design;

FIG. 6 is a top view of the new design; and,

FIG. 7 is a bottom view of the new design.

The broken lines shown are included for the purpose of illustrating unclaimed subject matter and forms no part of the claimed design.
